His Attorney

UNITED STATES PATENT OFFICE

GEORGE W. BAUGHMAN, OF WILKINSBURG, PENNSYLVANIA, ASSIGNOR TO THE UNION
SWITCH & SIGNAL COMPANY, OF SWISSVALE, PENNSYLVANIA, A CORPORATION OF
PENNSYLVANIA

RAILWAY SIGNALING SYSTEM

Application filed July 27, 1929. Serial No. 381,468.

My invention relates to railway signaling systems, and particularly to systems of the type involving direct current track relays operated from alternating track circuits through the medium of rectifiers.

One feature of my invention is the provision, in systems of this character, of means for preventing false operation of track relays in the event of failure of insulated rail joints, and also false operation of the track relays due to electric propulsion current.

I will describe one form of system embodying my invention, and will then point out the novel features thereof in claims.

The accompanying drawing is a diagrammatic view showing one form of signaling system embodying my invention.

Referring to the drawing, the reference characters 1 and 1^a designate the track rails of a stretch of railway track, which stretch is divided by insulated rail joints 2 into a plurality of successive sections, such as A—B and B—C. When the railway is of the electric propulsion type, it is provided with the usual inductive bonds 3 for conducting propulsion current around the insulated joints 2.

Each track section is provided with a source of alternating track circuit current, which, as here shown, is the secondary of a transformer designated by the reference character T with an exponent corresponding to the location. The frequency of the track circuit current supplied to each section is different from the frequency supplied to each of the adjoining sections, and as here shown, one section is supplied with track circuit current of 60 cycles per second and the adjacent one with 120 cycles per second. The two frequencies may be supplied to the primaries of the transformers T in any suitable manner, such, for example, as by two separate transmission lines or by local vibration generators of alternating current. As shown in the drawing, however, the 60 cycle current is supplied directly from a transmission line L,

whereas the 120 cycle current is supplied from this same transmission line through a full-wave rectifier H^B. That is to say, the primaries of transformers T^A and T^C are connected directly with the transmission line L, which is constantly furnished with 60 cycle current by a generator G, whereas the primary of transformer T^B is connected with the output terminals of a full-wave rectifier H^B, the input terminals of which are connected with the transmission line L. It follows that 120 cycle current is delivered to the track rails of section A—B.

Each track section is provided with a transformer designated by the reference character D with an exponent corresponding to the location, the primary of which is connected across the rails of the section. The secondary of each transformer D supplies track circuit current to a rectifier E, and this rectifier in turn supplies unidirectional current to a track relay R of the direct current type. Interposed between each transformer D and the associated rectifier E is a filter designated by the reference character F with an exponent corresponding to the location. Each filter is tuned to the frequency of the track circuit current supplied to the rails of the associated section. Each of these filters as here shown, comprises a condenser 4 and an auto-transformer 5, but this specific structure and arrangement of the filter elements is not essential.

It will be noted that when a given section is unoccupied, the associated track relay R will be energized because the filter F associated with such section freely transmits the track circuit current supplied to the section. I will assume, however, that the insulated joints 2 at the point B break down, thereby allowing alternating current from transformer T^B to be supplied to transformer D^B. This current is of 120 cycles, whereas the filter F^B is tuned to 60 cycles, with the result that the current from transformer

T^B which reaches the rectifier E^B will be insufficient to effectively energize track R^B. For similar reasons, the failure of any insulated rail joint will not result in the false energization of the relay for one of the affected sections by track circuit current from the other affected section.

If the railway is of the electric propulsion type and the propulsion current is alternating in character, the frequency of the propulsion current will be different from either of the frequencies of the track circuit currents. It follows that unbalanced propulsion current in the two track rails of any section will not result in false energization of the associated track relay because the propulsion current will not be transmitted through the associated filter F.

In the event that the propulsion current is direct, the alternating components of such current, due for example to commutator ripples, cannot cause false energization of the track relays R, because such components will be different in frequency from the frequencies to which the filters F are tuned, and, consequently, such components will be suppressed by these filters.

Although I have herein shown and described only one form of signaling system embodying my invention, it is understood that various changes and modifications may be made therein within the scope of the appended claims without departing from the spirit and scope of my invention.

Having thus described my invention, what I claim is:

1. In combination, a stretch of railway track divided into sections by insulated rail joints, a source of alternating track circuit current connected with the rails of each section, the frequency of the source for each section differing from the frequency of the sources for each adjacent section, a rectifier for each section receiving current from the rails of the section, a direct current track relay connected with the output terminals of each rectifier, and a filter interposed between the rails of each section and the associated rectifier and tuned to the frequency of the current supplied to the section, whereby if an insulated rail joint should fail the relay for one of the affected sections will not be falsely operated by track circuit current from the other affected section.

2. In combination, a stretch of electric railway divided into sections by insulated rail joints, a source of alternating track circuit current connected with the rails of each section, the frequency of the source for each section differing from the frequency of the sources for each adjacent section, a rectifier for each section receiving current from the rails of the section, a direct current track relay connected with the output terminals of each rectifier, and a filter interposed be-

tween the rails of each section and the associated rectifier and tuned to the frequency of the current supplied to the section, whereby if an insulated rail joint should fail the relay for one of the affected sections will not be falsely operated by track circuit current from the other affected section, and whereby the relays cannot be falsely operated by propulsion current.

In testimony whereof I affix my signature.

GEORGE W. BAUGHMAN.
